(57) **CLAIM**

The ornamental design for a disc jockey turntable, as shown and described.

DESCRIPTION

FIG. 1 is a perspective view of a disc jockey turntable showing my new design;

FIG. 2 is a top view thereof;

FIG. 3 is a bottom view thereof;

FIG. 4 is a front elevational view thereof;

FIG. 5 is a rear elevational view thereof;

FIG. 6 is a left elevational view; and,

FIG. 7 is a right elevational view thereof.

The broken line showing of a tone arm assembly on FIGS. 1-2 and 4-7 is for illustrative purposes only and forms no part of the claimed design.

1 Claim, 7 Drawing SheetsFIG. 1.

FIG. 2.

FIG. 3.

FIG. 4.

FIG. 5.

FIG. 6.

FIG. 7.
